UNITED STATES PATENT OFFICE.

WILLIAM EDENBORN, OF CHICAGO, ILLINOIS.

WIRE-FENCING MACHINE.

SPECIFICATION forming part of Letters Patent No. 653,339, dated July 10, 1900.

Application filed November 13, 1899. Serial No. 736,762. (No model.)

To all whom it may concern:

Be it known that I, WILLIAM EDENBORN, a citizen of the United States, residing at Chicago, in the county of Cook and State of Illinois, have invented certain new and useful Improvements in Wire-Fence Machines, of which the following is a full, clear, and exact description, reference being had to the accompanying drawings, forming part of this specification.

My present invention relates to that class of machines that are employed for making a continuous web of fencing consisting of longitudinal or strand wires tied together by transverse or stay wires.

My present invention consists in features of novelty hereinafter fully described, and pointed out in the claims.

Figure I is a detail view, part in front elevation and part in section, taken on line I I, Fig. III. Fig. II is a detail top view. Fig. III is a detail vertical section taken on line III III, Fig. II. Fig. IV is a detail front view showing part of the twisting-heads or spindles and part of the stay-wire holders. Fig. V is a top view of same. Fig. VI is a perspective view showing a fragment of the fencing that my machine is designed to make.

For a detail description of the general character of machines to which my present invention relates, reference may be had to my Patents No. 558,787, dated April 21, 1896, and No. 565,380, dated August 4, 1896.

This invention has reference to a means for holding and moving the stay-wire sections after they are cut off and to means for holding these sections against the ends of the coiling-spindles, so that the coiling-fingers will not fail to engage them.

1 represents part of the bed-plate of the machine, from which rises a standard or frame 2, that supports the parts. 3 are the spindles, through which the strand or longitudinal wires (indicated by dotted lines A) are fed. 45 There is a spindle for each strand-wire, and in practice they are preferably arranged in a vertical series. Each spindle is provided with a coiling-finger 4, as in the patents referred to. As the manner of mounting and turning these spindles forms no part of my present invention, no description of such parts is here

necessary. It may be done as in the patents referred to or otherwise.

The transverse or stay wires are indicated by dotted lines B. They are fed forward intermittently by suitable mechanism, as by rollers 5 and cams 6, (see Figs. I and III,) and they may be held from retrograde movement by spring-dogs 7. These wires are fed through suitable knives or cutters 8, which form no part of my present invention, and which may be constructed, arranged, and operated in any of the well-known ways.

I will now describe the parts to which my invention does relate.

Between the spindles 3 are disks or heads 10, mounted in the frame 11, to which the spindles are also journaled. These heads or disks are provided with grooves 12, (preferably made in removable face-pieces,) one wall

of the groove of each head being preferably undercut, as shown in Fig. V, and to the other wall is secured a flat spring 13. There is a disk 10 for each stay-wire, and the disks are capable of being turned a quarter of a revolution or thereabout, so as to be moved to

bring the grooves in line with the direction of feed of the stay-wires and from this position to one at substantially right angles thereto, or from the position shown at the right of Fig. IV to the position shown at the left of

Fig. IV. As a means for thus moving the disks I have shown them provided with arms 14, having a slot-and-pin connection with a bar 15, connected to one end of a pivoted lever 16, the other end of which engages a cam

17 on a shaft 18. As the shaft revolves the disks are rocked back and forth from a position which brings their grooves in line with the direction of feed of the stay-wires to a

position indicated at the left of Fig. IV. They are in the former position at the time that their respective stay-wires are fed forward, so that the wires enter the grooves in the disks. The parts of the machine are so

disposed that after the wires are fed into the disks the cutter of the machine severs the wires and the sections thus cut off are now held by the disks, and as the latter are turned from the position shown at the right of Fig. IV to the position shown at the left of Fig. IV the sections of wires are carried so as to

bring one end of each section beneath one of its strand-wires and the other end of the section over its other strand-wire, and as the sections are brought to this position their 5 ends are engaged by the coiling-fingers on the spindles, which twist them around the strand-wires, as shown in Fig. VI. After the sections are twisted about the strand-wires the fencing is moved forward by a suitable mechanism, not here shown, but which may be such 10 a mechanism as is found in my Patent No. 558,787, referred to, or any other suitable form of mechanism for this purpose may be used. As the fencing is thus moved forward, the 15 sections of stay-wires are drawn away from the disks 10, which release them, the spring 13 yielding sufficiently for this purpose. When the sections are drawn away from the disks, the latter are rocked back again to bring the 20 grooves in line with the direction of feed of the stay-wires, and upon the stay-wires being fed forward again they enter the grooves, as explained, and the operation of cutting the sections off and turning the disks to bring 25 the ends of the sections of the stay-wires in position to be coiled about the strand-wires is repeated, the parts being automatic in their action throughout.

As the wire comes from the reels it is not 30 perfectly straight, but has a set or curve in it, and this set, when the curve directs the ends of the wires in a direction away from the spindles, sometimes causes the coiling-fingers to fail to take a good hold on the ends 35 of the wires, and to overcome this to a measure, at least, I set the disks 10 slightly back from the extreme outer faces of the spindles, as shown in Fig. V, so that as the disks revolve to bring the ends of the wires against 40 the slightly-conical ends of the spindles the tendency will be to straighten the sections of wires, and to still further guard against danger of the fingers missing the ends of the wires I provide forks 20, (see Fig. I,) that are 45 secured to a head 21. The head is held in circular inclined slots 22, formed in extensions 23 of the frame 11. (See Fig. III.) The head is connected at each end by a rod 24 to a lever 25, pivoted at 26, and the other end 50 of which is engaged by a cam 27 on a shaft 28. As the sections of stay-wires are brought by the disk into position to be coiled about the strand-wires, as explained, the cams 27 cause the head 21 to move downwardly, bringing 55 the ends of the forks 20 against the sections of stay-wires and pressing the ends of the sections inwardly against the ends of the spindles, so that the coiling-fingers will take a firm hold of the ends of the stay-sections.

60 After the fingers have started to twist the stay-wires the cams 27 leave the levers 25 and the head 21 is then raised by the springs, one of which is shown at 30, Fig. III, to its upper position to carry the forks 20 out of 65 contact with the stay-wires, so that the fencing may be moved forward, as stated. By the use of these forks any set or curve in the

sections of stay-wires is taken out and the ends of the stay-wires are pressed inwardly, so that the coiling-fingers securely engage 70 them.

While only one of the extensions 23, with its slot 22, and only one of the rods 24, levers 25, and cams 27 are shown in the drawings, yet it will be readily understood how these 75 parts are duplicated at the other end of the machine.

I claim as my invention—

1. In a wire-fence machine, means for coiling the sections of stay-wires around the 80 strand-wires, in combination with means for holding said sections after they are cut off and by which the sections are turned to bring them against their respective strand-wires, substantially as set forth. 85

2. In a wire-fence machine, means for coiling the sections of stay-wires around the strand-wires, in combination with means for holding said sections after they are cut off and by which each section is turned to bring 90 one of its ends beneath one of its strand-wires and its other end over its other strand-wire, substantially as set forth.

3. In a wire-fence machine, means for coiling the sections of stay-wires around the 95 strand-wires, in combination with disks or heads adapted to receive the stay-wires and hold the sections after they are cut off, and means for turning said disks or heads to bring said sections against their respective strand-wires, substantially as set forth. 100

4. In a wire-fence machine, means for coiling the sections of stay-wires around the strand-wires, in combination with heads or disks provided with grooved faces to receive 105 the stay-wires, and means for turning said disks or heads after the stay-wires are cut off, to bring the sections against their respective strand-wires, substantially as set forth.

5. In a wire-fence machine, means for coiling the sections of stay-wires around the strand-wires, in combination with disks or heads located between said coiling means, and means for turning the disks or heads; each disk or head being provided with a groove 115 and a spring located in the groove, substantially as set forth.

6. In a wire-fence machine, means for coiling the sections of stay-wires around the strand-wires, in combination with disks or 120 heads located between said coiling means, and means for turning the disks or heads; each disk or head having a groove, one wall of which is undercut and to the other wall of which a spring is secured, substantially as 125 set forth.

7. In a wire-fence machine, the combination of spindles provided with coiling-fingers, disks or heads located between the spindles and which are adapted to receive and hold 130 the sections of stay-wires, and means for turning the disks or heads to bring said sections against their respective strand-wires, substantially as set forth.

8. In a wire-fence machine, spindles provided with fingers for coiling the stay-wires around the strand-wires, in combination with disks adapted to receive and hold the sections 5 of stay-wires, and means for turning the disks; said disks being set slightly back of the front ends of said spindles, substantially as set forth.
9. In a wire-fence machine, means for coiling the sections of stay-wires around the strand-wires, in combination with means for holding said sections after they are cut off, and for turning the sections to bring them against their respective strand-wires, and 15 means for straightening said sections, substantially as set forth.
10. In a wire-fence machine, spindles provided with fingers for coiling the sections of stay-wires around the strand-wires, in com- 20 bination with means for carrying said sections against their respective strand-wires, a movable head provided with forks, and means for moving the head, substantially as and for the purpose set forth.
11. In a wire-fence machine, the combination with spindles having conical ends and provided with coiling-fingers, of disks or heads located between the spindles and which are adapted to receive and hold the sections of stay-wires, and means for turning the disks 25 or heads to bring said sections against their respective strand-wires, substantially as set forth. 30

WILLIAM EDENBORN.
